CLAIM

The ornamental design for a marker pen probe, as shown and described.

DESCRIPTION

FIG. 1 is a perspective view of a first embodiment of the marker pen probe of the present invention.

FIG. 2 is a front elevation of the marker pen probe of FIG. 1. The rear elevation of the marker pen probe of FIG. 1 is identical to the front elevation.

FIG. 3 is a right side elevation of the marker pen probe of FIG. 1.

FIG. 4 is a left side elevation of the marker pen probe of FIG. 1.

FIG. 5 is a bottom view of the marker pen probe of FIG. 1.

FIG. 6 is a top view of the marker pen probe of FIG. 1.

FIG. 7 is a perspective view of a second embodiment of the marker pen probe of the present invention.

FIG. 8 is a left side elevation of the marker pen probe of FIG. 7. The right side elevation of the marker pen probe of FIG. 7 is identical to the left side elevation.

FIG. 9 is a front elevation of the marker pen probe of FIG. 7.

FIG. 10 is a rear elevation of the marker pen probe of FIG. 7.

FIG. 11 is a bottom view of the marker pen probe of FIG. 7; and,

FIG. 12 is a top view of the marker pen probe of FIG. 7. The broken line drawing in FIGS. 1-5 and 7-11 is for illustrative purposes only and forms no part of the claimed design.
